UNITED STATES PATENT OFFICE.

CLAIR E. GODDARD, OF OMAHA, NEBRASKA.

RECORDING APPARATUS.

1,351,902.

Specification of Letters Patent.

Patented Sept. 7, 1920.

Application filed December 16, 1919. Serial No. 345,446.

To all whom it may concern:

Be it known that I, CLAIR E. GODDARD, a citizen of the United States, residing at Omaha, in the county of Douglas and State 5 of Nebraska, have invented certain new and useful Improvements in Recording Apparatus, of which the following is a specification.

This invention has for its object to provide an apparatus for use in moving a flexible strip upon which may be entered, a large 10 number of names with designating numerals and other data, the construction to be such that recording of the data may be made 15 after the strip has been moved, and that the strip may be moved for the purpose of finding a required data.

The invention includes a box for containing 20 a pair of spools or cylinders upon which the strips may be mounted, means whereby either of the spools may be positively rotated or may rotate as idlers, and convenient means for assembling or disassembling the parts. Other features relating to novelty 25 and utility will be hereinafter described in detail.

In the accompanying drawing which illustrates one embodiment of the invention, Figure 1 is a side view of the apparatus. 30 Fig. 2 is a plan view of the same, the lid being elevated. Fig. 3 is a transverse section on line 3—3 of Fig. 1. Fig. 4 is a transverse section on line 4—4 of Fig. 1.

Fig. 5 is a plan view of the apparatus. 35 Fig. 6 is a side view of a latch. Fig. 7 shows a side view of a set-screw. Fig. 8 is a side view of a stub-shaft and one of the gear wheels. Figs. 9 and 10 show a pair of disks for engaging the ends of a spool or 40 cylinder. Fig. 11 is a plan view showing a terminal part of the flexible strip and Fig. 12 is an edgewise view of the same.

The apparatus consists, in part, of an 45 elongated casing 1 preferably rectangular in plan which may be placed on a counter or table when in use, said casing being provided with a lid 2 having an aperture 3 formed transversely therein midway between its ends, and also provided with a shelf 4 near its top midway between its ends, so that when the lid is lowered its aperture 50 will be disposed immediately above the shelf.

Disposed within the casing and transversely thereof, equidistant from the shelf,

are cylinders 5 and 6 each, preferably, being provided with a slot 7 formed longitudinally therein and provided with a recess 8 opening upon the slot.

Numerals 9 and 10 respectively indicate 60 disks, these being arranged in pairs, each disk 9 being provided at its middle with a depression or chamber 11 angular in plan, and each disk 10 being provided at its middle with a depression 12 preferably of cone- 65 shape.

Numerals 13 indicate a pair of apertured bearing-blocks or plugs which are removably mounted in suitable apertures formed in one of the sides of the casing for receiving 70 a pair of pivot-pins 14 which are adapted to engage in a depression 12 of a disk 10, each pin 14 being provided with a circular groove 15 for receiving a latch 16, said latches engaging in the grooves for preventing 75 end-thrusts and being pivotally mounted to swing from the inner side of the casing.

By the construction described, the cylinders 5 and 6 are provided with a pivotal 80 mounting for one of their ends, and it will be seen that the parts may be readily assembled and that the cylinders 5 and 6 may be removed from the casing whenever required by withdrawing the pins 14 after latches 16 85 have been swung upwardly from the grooves 15.

Numerals 17 and 18 indicate a pair of gear-wheels each being provided with a stub-shaft 19, said shaft having a circular 90 groove 20 formed therein and provided between its free end and the groove 20 with a boss 21 which is threaded thereon; that part of each stub-shaft adjacent to its cone-shaped end being formed angular in cross- 95 section for engagement within a chamber or angular depression 11 of a disk 9.

As described it will be understood that a revoluble movement of the gear wheels 17 and 18, in either direction, will cause a corresponding revoluble movement of the cylinders 5 and 6, the bosses 21 engaging the disks 9 to prevent end-thrusts of the cylinders, any end-thrusts of the shafts 19 being prevented by means of set-pins 22 which engage in grooves 20, the set-pins 22 being mounted in bearing-blocks 23 which are suitably secured to the side of the casing opposite to the bearing-blocks 13.

As described, and when the parts are as- 110

sembled, each stub-shaft 19 which projects inwardly of one side of the casing will be disposed in line with a pivot pin 14 which projects inwardly from the opposite side of the casing, the axes of these parts and the axis of a cylinder being coincident, so that the record-strip 24 employed may be suitably wound upon or unwound therefrom.

The strip 24 is preferably constructed of paper, but any flexible material may be used upon which may be written or printed any required data, lines 25 being formed transversely of the strip to provide spaces, and lines 26 being provided longitudinally of the strip to intersect the lines 25. Each end of the strip is provided, preferably, with projections 27 for engaging the inner wall of a cylinder while disposed in a slot 7 after entering a recess 8 as a means for removingably connecting the ends of the strip with the cylinders, and in operation, the strip may be moved longitudinally when being wound upon one of the cylinders, that part of the strip between the cylinders being supported upon the shelf or ledge 4.

The apparatus may have a variety of uses but is particularly adapted for the use of State, county and Federal officials in the matter of collecting taxes or for the use of insurance companies or the like where it is desirable to avoid delay in transacting business, the name of the firm, corporation or individual being written between the lines 25, and the data relating to the individual 35 being placed adjacent thereto, between the lines 26.

In order that the strip may be moved rapidly and in either direction, and that either one of the cylinders may be rotated positively while the other cylinder will rotate dependably, during operation, I provide a third gear wheel indicated at 28 and having a handle 29 for its manual rotation, said wheel 28 having axial bearings in one end 45 of a crank-arm 30, the opposite end of the crank-arm having a pivotal mounting in the side of the casing.

In operation, when it is desired to cause a movement of the strip in a direction of the cylinder 5 and to become wound thereon, the operator disposes the wheel 28 in engagement with the wheel 17 and rotates said wheel 28 in the direction of the long arrow shown in Fig. 1, the paper being supported 55 by the shelf in such a manner that names or data may be written thereon as above mentioned when making a record, and as is obvious, the proportion of parts may be such that the strip may be moved with considerable speed, this being a desirable feature when it is necessary to find a name or other data quickly, the cylinder 5 being positively rotated and the cylinder 6 rotating as an idler.

65 The cylinder 6 may be positively rotated

for causing a movement of the strip in a direction reverse to that last mentioned, the operator first causing a swinging movement of the crank-arm 30 to permit the gear wheel 28 to engage the gear wheel 18, and by use 70 of the handle 29 causing a rotation of the wheel 28 in a direction reverse to that indicated by the long arrow, the arc of movement of the crank-arm being from its pivotal mounting α as shown best in Figs. 1 75 and 4.

While I have shown and described construction in detail it has been for the purpose of explaining my preferred construction or one embodiment of the invention, 80 and I do not wish to be understood as limiting myself to these details, nor to form, size proportion or material to be used, and I may change details of construction within the scope of the invention as claimed. 85

I claim:—

1. A recorder comprising a casing, a shelf therein, a cover for the casing having an opening over the shelf, a pair of reels in the casing adapted to wind and unwind a web 90 back and forth over said shelf, each reel comprising a pair of end disks having depressions therein constituting bearing for the reel, one of the depressions being formed with angular walls, pivot pins journaled in the casing at one side and having ends engaging in the depressions of the adjacent disks, said pins having grooves therein, latches pivoted in the casing and normally resting in the grooves to lock the pins in 95 place, stub shafts journaled in the opposite wall of the casing and having angular ends for fitting in the angular depressions of the disks, pinions on said stub shafts, manually rotatable gear wheel journaled to swing alternately into and out of mesh with said pinions, and drums held between said disks and having means to detachably engage with the ends of the web.

2. In a recording device comprising a 110 casing, a shelf in the upper central portion of the casing, a hinged cover for the casing having an opening directly above the shelf, a pair of reels in the casing at opposite sides of the shelf and below the same, said reels 115 having a web wound thereon and passing over said shelf, each reel composed of a pair of spaced apart disks having depressions therein, one of said depressions having straight sides, a hollow drum secured to said 120 disks and having an axial slot therein with a wide recess at one end thereof for receiving the end of the web, means on the web for entering the recess but adapted to secure the web on the reel while in the slot, 125 bearing pins journaled in the said walls of the casing and entering the depressions in said disks, one of said pins being straight sided to fit the straight sided depression and form a driving connection therewith, pin- 130

ions exterior of the casing and mounted on the driving pin having straight sides, a swinging crank arm mounted above and between the pinions, and a hand-actuating gear wheel journaled on said arm and adapted to swing alternately into and out of mesh with said pinions.

In testimony whereof I have affixed my signature in presence of two witnesses.

CLAIR E. GODDARD.
